SPRAYING OR ATOMIZING SYSTEM.
APPLICATION FILED MAY 14, 1915.

Patented Aug. 27, 1918.

2 SHEETS-SHEET 2.

UNITED STATES PATENT OFFICE.

HERMAN EDWARD STURCKE, OF BROOKLYN, NEW YORK.

SPRAYING OR ATOMIZING SYSTEM.

1,277,269.

Specification of Letters Patent. Patented Aug. 27, 1918.

Application filed May 14, 1915. Serial No. 28,101.

To all whom it may concern:

Be it known that I, HERMAN EDWARD STURCKE, a citizen of the United States, and resident of Brooklyn, in the county of 5 Kings and State of New York, have invented certain new and useful Improvements in Spraying or Atomizing Systems, of which the following is a specification.

This invention relates to an improved 10 method of an apparatus for spraying or atomizing materials such as liquids or liquid compositions, and particularly for spraying liquid compositions such as paints by the use of gas stored in containers which 15 are preferably though not necessarily portable.

The object of the invention is to provide an improved method and apparatus of this character whereby the atomizing or spraying 20 can be effected by a constant stream of pressure gas.

Some preferred embodiments of my invention will now be described with reference to the accompanying drawing in which; 25 Figure 1 is perspective view showing a portable machine when not in use.

Fig. 2 is a perspective view showing a portable machine in use, said machine employing safety heating means and hereinafter described.

Fig. 3 is a section taken through the heating means of Fig. 1.

Figs. 4 and 5 show fragmentary views of modifications.

Fig. 6 is a horizontal section taken through a well-known regulating device employed in the present apparatus.

In accordance with the method of the present invention, which will be described with 40 reference to the preferred forms of apparatus herein illustrated, I use as the atomizing or spraying medium, carbon dioxid or other suitable gas under pressure, stored either in liquid or gaseous form in a container which is preferably portable, so that the container can be readily transported to the position where it is to be used to supply the gas for atomizing purposes. In carrying out my improved method, it is immaterial 45 whether or not the gas contained in the container is in liquid or gaseous form, inasmuch as this feature of my invention provides for the issuing of the carbon dioxid or the like from the container in gaseous 50 form, and by applying heat evenly to the stream of issuing gas before it has an oppor-

tunity to expand to a substantial extent, as by passing it through a coil arranged in a liquid bath at a temperature above normal atmospheric temperature and preferably as 60 high as possible, I have found from actual practice that the gas issuing from the container will not tend to freeze in the outlet of the container and moreover, when passed through a pressure reducing valve or regulating device, in order that its pressure may be reduced to that required at the atomizing or spraying tool, it will not freeze at the point of expansion. The gas may or may not be re-heated in similar manner, and is then 65 conducted to the spraying tool or receptacle for the material to be sprayed, or both to the receptacle and the tool. In addition to heating the issuing stream of gas in this manner, I sometimes find it desirable to heat 70 the container itself, either directly or indirectly or by means of a liquid bath or by applying steam or hot gases against the container, and this heating of the container 75 may or may not be effected by the same heating device which heats the liquid bath.

I will now proceed to describe my invention with reference to the preferred form of apparatus illustrated in Figs 1, 2 and 3. Referring to said figures it will be noted 80 that the apparatus comprises a platform 10, mounted on wheels 11 and 12. Riveted or otherwise suitably secured to the platform 10 are two vertical angle-iron frame members 13, braced by vertical side plates 14 85 which serve to support the axis of wheel 12. The wheels 11 are mounted in inclined bars 15, bolted at 16 to the uprights 13 and connected by the pins 17 to the side bars 18, secured at 19 to the uprights 13. A cross-bar 90 20 connects the two uprights 13, and a panel 21 is secured between the said uprights and serves as a support for the shelf 22 and the regulating means hereinafter described. Handles 23 are pivoted at 19 to the uprights 100 13 and are formed with the openings 24 adapted to take over the pins 17, so that said handles can be swung from the position shown in Fig. 1 to that of Fig. 2, and secured in position by passing the openings 105 24 over the pins 17. The cross-bar 20 forms a support for two hook-shaped members 25 bent at their ends nearest the cross-bar 20 to form an annular retaining means for the carbon-dioxid container 26. Said 110 members 25 are connected together by a bolt 25^a with wing-nut 25^b whereby the con-

tainer will be held between said members. The hook-shaped ends 27 of the bars 25 serve to support the paint receptacle 28 of any well-known type, as shown in Fig. 1, which receptacle will be removed to the most convenient position for painting as in Fig. 2. The container 26 for carbon-dioxid or the like is provided with a manually operable valve 29 which, when opened by turning the handle 30, permits the contents of said container to escape into the pipe 31, leading to the coil 32 immersed in a liquid bath 33 contained in tank 34 mounted on shelf 22 and heated by any suitable heating means, the device illustrated in Fig 1 being a well-known commercial type of kerosene burner 35. The gas leaving the coil 32 passes up through pipe 36 into the regulating means 37 and associated gage and indicator 38 mounted on panel 21 and illustrated more particularly in Fig. 6, where the pressure of said gas is suitably reduced; the extent of this reduction can be regulated in well-known manner by means of the handle 39. The outlet 40 of the regulator 37 is connected with a pipe 41 leading to coil 42 which is also immersed within the liquid bath 33, and connected with the other end of this coil is a pipe 43 leading to a valve 44 which controls the passage of gas from said pipe 43 to pipe 45 to which is connected a flexible pipe 46 (Fig. 2) preferably made of rubber or the like, and leading to the paint receptacle 28. The flexible pipe 46 is connected with the interior of the paint receptacle by the T-connection 47 which provides a branch 48 leading to the regulating means 49, which is similar to the regulating means 37 and adjustable by the milled head 50, whereby the pressure on top of the paint can be regulated to suit the requirements for use. The pipe 51 leads from the other end of said T-connection 47 to the painting tool or brush 52 of well-known kind, whereby the compressed gas is supplied to said tool.

The paint under pressure, forced by the compressed gas on the top of the paint receptacle 28 through the outlet 54 passes into the flexible pipe 55 leading to the painting tool, where the atomization of the issuing paint is effected by the pressure gas from the pipe 55.

The operation of the improved painting apparatus will now be described. The paint receptacle 28 is removed from the hook 27 and placed upon the ground, as shown in Fig. 2, and the burner 35 is lighted in order to heat the liquid contained in the tank 34. The carbon dioxid or like gas under pressure in the container 26 is then permitted to leave said container by opening the valve 29, which allows said gas to pass through pipe 31, coil 32, pipe 36, pressure regulator 37, pipe 41, re-heating coil 42, pipe 43, valve 44,

pipe 45, flexible connection 46 to paint receptacle 28. The gas passing through the pressure regulating valve 49 to the top of the paint receptacle forces the paint in said receptacle at the desired pressure through the pipe 55 into the painting tool, and the compressed gas passing through the T-connection 47 to the pipe 51 also passes through the painting tool under the required pressure to atomize the paint. It will be understood from the above that the gas reaches the heater without substantial expansion, so that no freezing occurs during the passage of the gas through the pipe 31 to the coil 30. Care should be taken not to use too wide a pipe. 80

The devices which are herein referred to as pressure regulating valves are of well-known character, and in the example of the regulator 37 herein shown, as illustrated in Fig. 6, comprises a casing 56 formed by two members 57, 58 between which is suitably secured a diaphragm 59 upon which is mounted a seat-supporting member 60 provided with a seat 61 covering the small opening 62 at the conical end 63 of pipe 64 leading from the elbow 65 for the admission of gas. Bearing on the other side of said diaphragm is a spring 66 the tension of which can be regulated by means of a nut 67 mounted on screw shaft 68 in the casing and provided with the operating handle 39. A pipe 69 at the top of the casing which cannot be seen in this figure, but is visible in Fig. 3, leads to the indicating device 38 (Fig. 3), and the outlet 40 conducts the gas at the reduced pressure to the pipe 41 (Fig. 3). While this is a preferred form of pressure regulating or reducing valve, it will be understood that the invention contemplates the employment of any suitable or well-known form of device of this character. 100

The container 26 may contain either carbon dioxid or like gas under pressure or in liquified form, and may or may not be provided with well-known siphon means for leading the carbon dioxid to the outlet valve 29. 110

In the modification shown in Fig. 4, steam generated by heating the water bath 33^a is applied against the side of the container 26^a 115 in order to heat the contents of the container during the painting operation. In this modified form, the tank 34^a is provided with a cover 35^a which serves as a support for one or more nozzles 36^a controlled by the valve 120 37^a and which is adapted to direct the steam generated in the tank 34^a against the side of the container 26^a. In Fig. 5, the hot combustion gases from the burner 38^a pass through the opening or openings 39^a in the 125 supporting shelf 22^a and panel 21^a, and are directed against the sides of the container 26^a, thereby heating the contents of the container as well as the tank. A slide 40^a with an opening 41^a is arranged between the shelf 130

22^a and panel 21^a and regulates the passage of hot gas through the openings 39^a.

In painting the interior of certain buildings, in order to comply with fire regulations 5 and for the general purpose of safety, I may use a Davy lamp for the purpose of providing the necessary heating. Fig. 2 shows the use of such a lamp, which is provided with the usual perforated screen 35^b. Alternatively, as shown in dotted lines in Fig. 5, I 10 may employ an electrical heating coil 70 immersed in the liquid, and supplied with heating current from a battery 71, which may be carried upon the platform of the portable 15 painting apparatus, the current from the battery passing through the electrical connections 72, 73 controlled by switch 74. In place of using a battery as a source of current supply, it will be obvious that the connections 72, 73 can be connected to electric 20 mains, or to the ordinary electric light sockets in a house or the like by means of a suitable plug of a well-known character. In conjunction with the use of an electrically 25 heated coil or the like, instead of using a bath of water or the like to maintain an even temperature for heating the coils 32, 42, I may employ a bath of toluol, paraffin or the like, which present important advantages in 30 that a maximum temperature can be maintained without requiring any attention on the part of the operator, and there will be no evaporation of the liquid contents of the tank 34.

35 I prefer to heat the gas in the liquid bath as much as possible, as this materially assists in getting the best results.

While the improved apparatus has been described herein with reference to a method in which the carbon dioxid or the like leaves the container in gaseous form, it will be understood that my improved apparatus is suitable for use in cases where the carbon dioxid leaves the container in liquid form.

45 While my improved method and apparatus have been described herein with reference to the spraying or atomizing of paint, it will be understood that I contemplate the use of this apparatus with obvious modification for any kind of atomizing or spraying operation, such as the atomizing of metals or sand blast apparatus, and it will be obvious that many changes will be made in the herein described method and apparatus 50 without departing from the spirit of my invention and the scope of the appended claims.

What I claim is:—

1. Method of atomizing or spraying ma-

terial such as paint by means of carbon dioxid in a pressure container, consisting in leading a stream of high pressure carbon dioxid gas from said container through a heated liquid bath, thereby heating said gas, reducing the pressure of said heated gas, 60 leading said gas at reduced pressure through a heated liquid bath whereby to re-heat said gas, and subjecting the material to be sprayed to the action of said gas.

2. Method of atomizing or spraying material such as paint by means of carbon dioxid in a pressure container, consisting in leading a stream of high pressure carbon dioxid gas through a heated liquid bath, then reducing the pressure of said gas, and 75 subjecting the material to be sprayed to the action of said gas.

3. Method of atomizing or spraying material such as paint by means of gas in liquid form in a pressure container, consisting in 80 leading a stream of said gas in gaseous form at high pressure from said container through a heated liquid bath, then heating said gas, and subjecting the material to be sprayed to the action of said gas.

4. Apparatus for atomizing or spraying material such as paint by means of pressure gas consisting of a pressure container, a liquid bath, a receptacle for the material to be sprayed, a spraying tool, means for heating said liquid bath, means for leading the contents of said container through said bath, pressure reducing means, means for leading the contents of said container through said pressure-reducing means after leaving said 90 liquid bath, and means for leading said container to the material to be sprayed.

5. An atomizing apparatus comprising a pressure container, a liquid bath, a receptacle for the material to be sprayed, a spraying tool, means for heating said liquid bath, means for leading the contents of said container through said bath, pressure-reducing means, means for leading the contents of said container through said pressure-reducing means after leaving said liquid bath, a re-heating means connected with said pressure-reducing means, and means for leading said contents of said container to the material to be sprayed after passing through 105 said re-heating means.

Signed at Brooklyn, in the county of Kings and State of New York, this 13th day of May, A. D. 1915.

HERMAN EDWARD STURCKE.
